UNITED STATES PATENT OFFICE.

HARRISON H. BROWN, OF FOND DU LAC, WISCONSIN.

SAD-IRON HEATER.

SPECIFICATION forming part of Letters Patent No. 740,083, dated September 29, 1903.

Application filed June 17, 1903. Serial No. 161,934. (No model.)

To all whom it may concern:

Be it known that I, HARRISON H. BROWN, a citizen of the United States, residing at Fond du Lac, in the county of Fond du Lac and State 5 of Wisconsin, have invented certain new and useful Improvements in Sad-Iron Heaters, of which the following is a specification.

This invention provides a novel contrivance to facilitate the heating of sad-irons 10 and for confining the heat so as to prevent a ready escape therefor and a cooling of the irons by air currents or drafts. The contrivance is constructed with a view for use in connection with a stove or heater of any 15 type, the box receiving the iron being provided with either a grated bottom or a closed bottom, as desired, and according to the type of stove or heater with which the device is adapted to be used. For stoves or heaters 20 burning fuel tending to give off free carbon it is desirable that the bottom of the box be closed; but for heaters which give off no free carbon when in operation and burn with a clear fire it is preferable to have the bottom 25 of the box either grated or open.

A vital feature of the invention is the provision of novel means for automatic actuation of the door or cover when it is required to place a sad-iron within the box to be heated, 30 said cover closing after the iron has been received within the box.

For a full description of the invention and the merits thereof and also to acquire a knowledge of the details of construction of the 35 means for effecting the result reference is to be had to the following description and drawings hereto attached.

While the essential and characteristic features of the invention are susceptible of modification, still the preferred embodiment of the 40 invention is illustrated in the accompanying drawings, in which—

Figure 1 is a perspective view of a sad-iron heater embodying the invention. Fig. 2 is a 45 longitudinal section thereof. Fig. 3 is a perspective view of a modification. Fig. 4 is a transverse section on the line X X of Fig. 2.

Corresponding and like parts are referred to in the following description and indicated 50 in all the views of the drawings by the same reference characters.

The body of the heater is of box form, as

illustrated at 1, and its bottom, which may be closed or grated, is provided with an extended portion 2 to fit within a stove-opening after 55 the cover has been removed. The box 1 may be of any size and form, depending upon the number of irons to be heated, and is preferably of rectangular construction. The upper portion of the box is provided with an outer flange 60 3 to present a finished appearance and to give additional strength to the device.

The cover 4 is hinged near its rear end and is adapted to open upward at its outer end, as shown most clearly in Fig. 1. Journals 5 65 project outward from opposite sides of the cover a short distance from the rear end and are received in the space formed between pairs of lugs 6, projected upward from the box or body portion 1 of the heater. By 70 hinging the cover to the box in this manner it may be readily removed or placed in position as required. The cover is provided with a series of slots 7 to receive the handle portion 8 of the sad-irons 9 when the latter are 75 in position for heating. Lugs 10 project upward from the rear end of the cover and are provided at their outer ends with guards 11 to prevent lateral displacement of the spring-arms of the bail. The lugs 10 provide pressure-points which receive the perpendicular thrust of the bail when depressed at its outer end to effect an opening of the cover to admit of the sad-iron readily entering the box when 80 it is required to place the same therein. The 85 bail 12 is approximately of U form and is constructed of stout wire or light bar metal, and its side members have their terminal portions bent inward, as shown at 13, to pass through openings of lugs 14, projected upward from the rear end of box 1. The side members are offset near their pivotal ends, as shown at 15, so as to clear the cover 4 and not interfere with the free opening and closing movements thereof, as indicated most 90 clearly in Fig. 1. The offset portions 15 are about in line with the axis of the cover. The outer end of the bail projects beyond the outer end of the cover 4, so as to admit of the nose of the iron engaging therewith and pressing 95 down thereon to effect a raising of the cover preliminary to entrance of the sad-iron into the box. The side members of the bail are adapted to move laterally, thereby admitting 100

of the bail being applied to the lugs 14 or disconnected therefrom. The side members spring inward sufficiently to hold the bent ends 13 in engagement with the lugs 14; but 5 to guard against displacement of the parts 13 from the lugs 14 the extensions 11 are provided and engage with the outer sides of the longitudinal members of the bail, as indicated most clearly in Figs. 1 and 3.

10 When the parts are properly assembled, the outer end of the bail inclines upwardly and forwardly and the inner end rests upon the lugs or extensions 10. The weight of the 15 cover is such as to hold the outer end of the bail elevated; but in the event of the cover being constructed of sheet metal or like material said cover is weighted, as indicated at 16, to insure its counterbalancing the bail and holding the outer end thereof elevated. When 20 it is required to place a sad-iron within the box, the nose or front portion of the iron is engaged with the outer end of the bail and the latter depressed, thereby causing the outer end of the cover 4 to correspondingly rise a 25 distance to admit of the iron being moved forward, so as to engage under the cover when the iron may be conveniently placed within the box. After the iron clears the bail the cover automatically closes. When removing 30 the iron from the box, the cover is raised by contact of the iron therewith, thereby permitting the outer end of the bail to lower, so as to rest upon the box, and thereby not obstruct the removal of the iron or require lifting the 35 same, so as to clear the bail in its elevated position.

In the construction shown in Fig. 3, which is substantially the same as that shown in Fig. 1, a roller 17 is fitted to the outer portion

of the bail and a corresponding roller 18 is 40 applied to the front end of the box, and these two rollers constitute a rotary support for the iron when sliding the same into and from the box when resting thereon.

Having thus described the invention, what 45 is claimed as new is—

1. In a sad-iron heater, the combination of a box, a cover hinged thereto and having upward extensions in the rear of the axial line of the cover and having guards at the outer ends of said vertical extensions, and a bail pivoted to the box and resting upon the vertical extensions of the cover and held from casual displacement by the guards thereof, substantially as set forth. 55

2. A sad-iron heater comprising a box having spaced lugs near its rear end and transversely-apertured lugs at its rear end, a cover having longitudinal slots extended therein from its front end and having lateral journals 60 near its rear end to enter the space formed between the pairs of lugs and having vertical extensions in the rear of the axial line, a bail having its end portions inwardly bent and passed through the openings of the aforesaid 65 transversely-apertured lugs and resting upon the vertical extensions at the rear end of the cover and normally held elevated at its outer end by said cover, and guards at the outer ends of said vertical extensions to embrace 70 the side portions of the bail near their pivotal ends, substantially as set forth.

In testimony whereof I affix my signature in presence of two witnesses.

HARRISON H. BROWN. [L. S.]
